UNITED STATES PATENT OFFICE

FRANK H. KNEELAND, OF CHICAGO, ILLINOIS, ASSIGNOR TO SAFETY MINING COMPANY,
OF CHICAGO, ILLINOIS, A CORPORATION

BLASTING CARTRIDGE

Application filed October 19, 1929. Serial No. 400,838.

This invention is concerned with an improved blasting device intended for use with the ordinary forms of explosives. It is a matter of common knowledge that the use of such explosives in accordance with current practice in mines is dangerous and this is particularly true of gaseous mines. It is also well known that the action of such explosives on some substances, such as coal, is objectionably severe in that the product is 10 badly shattered.

An object of the present invention is to provide a blasting device with which any of the ordinary forms of explosives may be used, but without the objectionable results produced by such explosives when used in accordance with current practice.

Specifically, it is an object of the invention to provide an improved blasting device employing an ordinary explosive and wherein the severity of the explosion is reduced to a minimum.

It is also an object of the invention to provide a blasting device of the character indicated and wherein means are provided for the purpose of reducing the danger of mine explosion or fire.

In the drawing,

The single figure is a view in longitudinal section of a blasting device embodying my invention.

The method and apparatus of the present invention consists essentially of the use of an explosive medium in conjunction with a body of substantially incompressible fluid in such a way that the force of the explosion is caused to act through the body of fluid and the flame resulting from the explosion is substantially quenched by the fluid. The particular structure shown in the drawing comprises an indestructible cylinder 1, having a cap 2 secured over one end thereof. The interior of the cylinder is designed to receive a charge of any desired explosive such, for example, as black powder and an electric squib or matchhead 4 is provided to ignite the same. The leads from the matchhead or squib extend outwardly through an aperture 5 in the cap 2. The opposite end of the cylinder is provided with a shoulder 6 on which

is seated a water proof plug or wadding 7. The open end of the cylinder is enclosed by a container 8 which may be secured to the end of the cylinder by means of suitable clamping bands 9. The container 8 is so constructed and designed that it will rupture in response to a predetermined pressure and for this purpose the container may be formed of a heavy fabric or any suitable light metal. The container is adapted to be substantially filled with an incompressible fluid as indicated at 10.

In the use of a cartridge as above described, the entire device including the indestructible charged cartridge 1 and the rupturable fluid container 8 is inserted in the bore hole formed in the material to be blasted. After being properly positioned and tamped in place, the leads from the squib or matchhead may be connected to any suitable blasting device and the cartridge fired in the ordinary way. The result of ignition of the explosive will blow out the disc or wadding 7 and discharge the gases resulting from the combustion of the explosive directly into the body of fluid within the container 8. Thus, the container 8 will be ruptured by the increase in pressure therein and the force of the explosion will be exerted upon the material to be blasted through the medium of the liberated body of fluid.

The outstanding advantages of a blasting device as herein described are first, that the shock resulting from the explosion is minimized by the body of fluid and second, that the fluid serves to quench whatever flame may be produced by the combustion of the explosive material.

I claim:

1. A blasting cartridge comprising a metallic body having a chamber open at one end and adapted to be filled with an explosive, a fluid container secured to the open end of said body, and a rupturable closure for the open end of said body to separate the interior of said container from said chamber.

2. A blasting cartridge comprising an indestructible cylindrical body adapted to be charged with an explosive, an indestructible closure for one end of said body, a rupturable

water proof plug for the other end of said body, and a rupturable fluid container having an open end extending over and secured to the last mentioned end of said body.

5 Signed at Chicago, Illinois, this 17th day of October, 1929.

FRANK H. KNEELAND.
